UNITED STATES PATENT OFFICE.

NEAL F. MEARS, OF CHICAGO, ILLINOIS.

MUSICAL TRANSPOSING DEVICE.

Application filed May 14, 1919. Serial No. 297,059.

To all whom it may concern:

Be it known that I, NEAL F. MEARS, a citizen of the United States, and a resident of Chicago, in the county of Cook, State of Illinois, have invented certain new and useful Improvements in Musical Transposing Devices, of which the following is a specification.

My invention relates to an improved transposing chart which is particularly useful in the musical field for the transposition of music.

Among the important objects of my invention are: to provide a simple, inexpensive device for calculating musical transposition; to provide a device to illustrate the basic principles of transposition for all instruments and the law governing their pitches and the keys of their respective parts; to provide a device to enable the veriest novice, knowing merely the process of reading and writing notes and key signatures and having no knowledge of the fundamental laws of music, to correctly transpose; to provide a device to show transposition by placing the chromatic scale of one key adjacent to the chromatic scale of another key so that the notes in the two scales can be compared, and the process of transposition will thus be simplified into a matter of comparison; to provide a device by means of which transposition can be readily made from one note to another, from one key to another, from any instrumental part so that any other instrument can play it, from one clef to another; and in general to provide an improved and simplified structure which will illustrate these and many other transpositions or reorganizations of music.

My improved device is disclosed on the accompanying drawing in which

Fig. 1 is a plan view of the device with part of the upper disc broken away,

Fig. 2 is a vertical diametral sectional view, and

Fig. 3 is a plan view of the inner part of the device showing a different relative position of the disc members for giving such information.

The structure shown comprises three members, a large or bottom disc, an upper or smaller disc, and an intermediate disc. These members are connected to be adapted for relative parallel movement either in straight lines or along curved lines. In the

device shown the disc members are circular and are pivoted together at their centers to adapt them for relative rotational movement. The large or base disc 10 has the outer and inner rows 11 and 12 printed thereon, these rows being circular and concentric. In the outer row are the staff notations comprising key signatures and chords of the corresponding major or minor keys. In the inner row are the staff notations comprising the notes of the respective major or minor scales. The notes are in radial alignment with the respective key signature staff notations and these radially aligned staff notations are within segmental fields with radially extending blank spaces 13 between the fields. The key signatures and the scale notes are arranged in chromatic order, reading clock-wise, and the scale notes when successively read form complete chromatic scales. Associated with each segmental field outside of the outer row are the legends 14 indicating the number of sharps or flats of the respective keys, as for example 5b 2#, etc. Associated with each segmental field and between the outer and inner staff notations thereof is a legend 15 giving the names of the major or minor key of the respective signatures as for example D major-B minor. Just inside of the inner circle and associated with each segmental field is a legend 16 giving the name of the note shown, as for example D#, E, F, etc.

The upper disc member 17 and the intermediate disc member 18 are pivoted concentrically on and with reference to the base member 10, as by means of the eyelet e. On the member 17 around its periphery are the note staff notations 19 corresponding in arrangement and number with those in row 12. The intermediate member 18 has arranged in a circle just within the row or circle 19 the circle 20 containing the same key signature and chord staff notation fields as the outer row 11 of the base member 10, except that the order is reverse, that is, the designated fields read progressively in counterclock-wise direction on the intermediate member. The same legends are provided on the intermediate member as on the outer row 11 of the base member. The upper member 17 has a segmental part cut out therefrom to leave the segmental sight opening 21 in register with the staff notation circle 20 on the intermediate member. The intermediate member has a sight frame

extending therefrom comprising the sides or radially extending arms 22 and 23 and the circumferentially extending outer connecting bar 24, this bar being preferably outside 5 of the periphery of the base member 10. The arms 22 and 23 are spaced apart to fit the blank radial spaces 13 between the segmental fields on the base member 10. When 10 these arms engage in adjacent radial spaces they and the bar 24 will enclose a sight opening in which appears the segmental staff notation field between the respective radial spaces, and reading of all the matter in the 15 enclosed field and the adjacent fields is not interfered with. The location of the sight frame on the intermediate member should preferably correspond with the location of the sight opening on the upper member, that is, the sight frame should extend from that 20 key signature on the intermediate member corresponding to the note on the upper member adjacent which the sight opening appears. On the structure shown the sight opening 21 is adjacent the note C, while the 25 sight frame on the intermediate member extends from the key signature C major A minor. If the location of the sight frame is shifted the location of the sight opening should be correspondingly shifted. For example, suppose that the sight frame is shifted 30 to extend from the key signature D major-B minor, then the sight opening 21 would have been shifted to be adjacent the note D.

35 It will be noted that on the lower disc the staff notations for the keys F $\sharp$ major and D $\sharp$ minor are grouped in the same segmental field with the staff notations for the keys G $\flat$ major and E $\flat$ minor, and that on the 40 intermediate member these joined notations are not reversed but appear in the same relative position as on the lower disc member. This is for the purpose of enabling transposition to be made from the row 12 45 to the row 19 directly and not by cross reference, thus facilitating the transposing operation.

The operation of my improved transposing chart can now be readily understood.
50 Suppose it is desired to transpose from one key to another, say from the key of C to the key of Eb. The procedure is illustrated in Fig. 1. The intermediate disc 18 is rotated until the staff notation field for the 55 key of C appears within the indicator frame 22, 23 and 24. The upper member 17 is then rotated until its slot 21 reveals the staff notation for the key Eb on the circle 20. With this setting transposition from 60 the key of C to the key of Eb can be proceeded with. The notes of the work to be transposed are successively located on the large or base disc, and radially inside of each such note will be found the correspond- 65 ing note of the key to which transposition

is being made. For example, the note D of the work to be transposed becomes the note F in the new key, the note F of the work becomes the note A_b in the transposed key, and so on.

Music for the piano, violin or voice is often transposed so that cornets, clarinets, flutes, saxophones, horns and other instruments can play it. My device is particularly adapted for such transposition. Suppose it is desired to transpose music written in the key of D_b so that it can be played on a B_b cornet. Referring to Fig. 3, the operation is as follows: The upper disc is rotated until the note C thereon is directly under the notation of the key of the instrument, that is B_b . The intermediate member of the device is now rotated until the key of the music to be transposed,—in this case D_b ,—is indicated between the arms 22 and 23. After such transpositional setting the slot in the upper disc will show the new key necessary so that a B_b cornet can play the music which was written in the key of D_b , the new key being E_b . To transpose the music to the new key the notes are successively located on the large disc and the corresponding notes of the new key located radially within on the upper disc.

A great many other transpositional problems can be worked out on my improved device, as for example, transposing from one clef to another, or transposing any instrumental part so that any other instrument can play it. The operation of the device is very simple. It involves only three adjustable members, and after a setting the required information is clearly visible and definite. Only rudimentary knowledge of music is necessary and after a setting any transposition becomes merely a matter of copying from the upper disc the notes transposed from the lower disc. There is no chance for error, as the transposed note appears directly radially within the original note. 100 105 110

I do not, of course, desire to be limited to the exact construction, arrangement and operation shown and described as changes and modifications might readily be made which would still come within the scope of my invention. 115

I claim as new and desire to secure by Letters Patent:

1. In a transposing device the combination of a lower disc member having an outer row of key signature notations thereon, and an inner row of key note notations thereon, an upper disc member having a row of key note notations thereon corresponding to the key note notation row on said lower disc member, an intermediate disc member having a row of key signature notations thereon reading in reverse order to that of the key signature notation row of said lower 130

disc member, each member being movable relative to the other members, said upper disc member having a sight opening in register with the notations on said intermediate 5 disc, and a sight frame extending from said intermediate member for selecting the notations on said lower disc member.

2. In a transposing device of the class described, the combination of a lower disc 10 member having an outer row of key signature staff notations thereon and an inner row of notes thereon arranged in chromatic order, an upper disc member having a row of notes thereon corresponding to those 15 on the lower member, an intermediate disc member having a row of key signature notations thereon corresponding with those on the lower member but reading in reverse order, said upper disc member having a 20 sight opening adjacent one of the note indications thereon and registering with the indications on said intermediate member, and a sight frame extending from the intermediate member at the corresponding key 25 indication thereon for selecting the indications on the lower disc member.

3. A musical transposing device comprising a base member, an upper member, and an intermediate member, said members being 30 connected for movement along side each other, key signatures and corresponding scale notes placed in spaced apart fields along the outer edge of the base member, a sight frame extending from said intermediate member to enclose a selected field on the base member, key signature notations around the periphery of said intermediate member corresponding to the key signature notations on the base member but readable 35 in reverse order, note notations on the upper member, said upper member having a sight opening in register with the notations on the intermediate member.

4. In a musical transposing device, a plurality 45 of relatively movable members having notations arranged in fields separated from each other by spaces, a plurality of members each having an indicating means whose sides extend along said spaces to enclose a 50 selected field.

5. A transposing device of the class described comprising three relatively shiftable members, two of said members having adjacent rows of notes forming complete 55 chromatic scales, key signature notations on said members corresponding with the notes of said scales, and indicating means on two members co-operating with said key signature notations to determine the setting from 60 said scale-containing members for the transposition of one scale to another.

6. A transposing device comprising one member having a row of notes thereon arranged to form a complete chromatic scale, 65 a second member having a similar row of

notes thereon parallel with the row on the first member, said first member having key signature staff notations thereon corresponding with the notes on said member, a third member having key signature staff notations thereon corresponding with those on the first member, and locating means on said members whereby setting thereof may be accurately made to bring said chromatic scales into the proper relative position for 70 transposing from one scale to the other.

7. A transposing device comprising two chromatic scales each having key indicating means associated therewith, said scales being movable alongside each other to be set 75 for the transposition from one key to another.

8. A music transposing device comprising two chromatic scales composed of similar characters and each having key indicating 85 means associated therewith, said scales being movable alongside each other to be set for the transposition from any one key to any other key.

9. A transposing device comprising a plurality of members pivoted together for relative rotation, one of said members having segmental fields separated by radially extending spaces, each field containing the note identification of one of the twelve different 90 tones of the chromatic scale and the signature and chord of the key in staff notation, another of said members having fields each containing the note identification of one of the twelve different tones of the 100 chromatic scale, the third member having fields containing the signature and chords of the key in staff notation corresponding to the signatures and chords on the first mentioned member, and indicating means 105 for setting said members relatively for the transposition of notes or from one key to another.

10. A transposing device comprising two note identification rows and two key signature rows, the said note identification rows being movable alongside each other to be set for the transposition from one key to another and each note identification row having associated therewith a key indicating 110 means operating on a separate key signature row.

11. A transposing device comprising two note identification rows and two key signature rows, the characters in each row being 115 arranged in sections and there being blank spaces between each two sections, the said note identification rows being movable alongside each other to be set for the transposition from one key to another and each note 120 identification row having associated therewith a key indicating means operating on a separate key signature row.

12. A transposing device comprising note identification rows and key indicating nota- 130

- tions, the said key indicating notations being separate from the note identification rows and each note identification row having associated therewith a key indicating means 5 operating on separate key indicating notations.
13. A transposing device comprising note identification rows and key indication rows, the said key indication rows being separate from the note identification rows and each note identification row having associated therewith a key indicating means operating on a separate key indication row.
14. A transposing device comprising note identification rows and key indicating notations, the said note identification rows being movable to be set in position for transposing from one key to another and a plurality of said note identification rows having associated therewith separate key indicating means operating on separate key indicating notations.
15. A transposing device comprising note identification rows, each note identification row having associated therewith a separate key indicating means, the said note identification rows being movable to be set in position for transposing, by comparison of characters in said note identification rows, from one key to another.
16. A transposing device comprising relatively movable members, one of said members having a complete chromatic scale of notes, another of said members having a similar scale arranged alongside the first mentioned scale and each scale bearing mem- 50
ber having associated therewith means for determining the setting of said members for the transposition of notes from one key to another. 40
17. A transposing device comprising note identification groups, on separate members and each having associated therewith key indicating means whereby each note identification group is associated with a definite key. 45
18. A transposing device comprising note identification groups, on separate members and each having associated therewith key indicating means, the said note identification groups being so arranged that transposition may be made by comparison of characters in said note identification groups. 50
19. A transposing device comprising members, each of those which bear note identification groups having associated therewith key indicating means, the said members being movable to be set in position for transposition by comparison of characters in said note identification groups. 55
20. A transposing device comprising members, each of those which bear note identification groups having associated therewith key indicating means, the said members being so arranged that the view of all characters in said note identification groups in use is entirely unobstructed when setting is made for transposition by comparison of characters in said note identification groups. 60
65

In witness whereof, I hereunto subscribe my name this 12th day of May, A. D. 1919.
NEAL F. MEARS.
